UNITED STATES PATENT OFFICE.

FRANK E. OTT, OF INDIANAPOLIS, INDIANA.

ROAD-DRAG.

No. 893,259.

Specification of Letters Patent.

Patented July 14, 1908.

Application filed February 27, 1908. Serial No. 418,009.

To all whom it may concern:

Be it known that I, FRANK E. OTT, a citizen of the United States, residing at Indianapolis, in the county of Marion and State of Indiana, have invented certain new and useful Improvements in Road-Drags; and I do declare the following to be a full, clear, and exact description of the invention, reference being had to the accompanying drawings, 10 and to the letters and figures of reference marked thereon, which form a part of this specification.

This invention relates to the type of drags that are designed to be used on highways or 15 streets for scraping and leveling the surfaces thereof, the invention having reference particularly to adjustable drags of the above-mentioned character.

Objects of the invention are to provide a 20 relatively light weight strong drag adapted to be constructed at moderate expense, and to provide a drag of simple construction that may be adjusted readily so as to operate equally well on either hard or relatively soft 25 roads surfaced either with earth or with gravel.

The invention consists in an improved drag comprising an angle iron frame, scraping blades of improved construction, connected in a novel manner to the frame so as to be adjustable relatively thereto, and improved adjusting and controlling mechanism for the blades, the invention consisting further in the parts and combinations and arrangements of parts as hereinafter particularly described and defined in the appended claims.

Referring to the drawings Figure 1 is a perspective view of the improved drag; Fig. 2, 40 an end elevation thereof and showing the movable or adjustable parts in various positions by broken lines; Fig. 3, a fragmentary vertical sectional view approximately at the plane of the line A A in Fig. 2; and, Fig. 4, a fragmentary sectional view of a controlling lever and latch therefor.

Similar reference characters in the various figures of the drawings designate corresponding elements or features of construction.

The invention practically embodied comprises a suitable frame which may advantageously be composed principally of standard sizes of angle iron bars.

The frame comprises two counterpart 55 beams *a* and *a'* forming the main central portions thereof and two similar end beams *b*

and *b'* that are slightly longer than the other beams, an angle iron brace *c* being secured to the beam *b* near the forward end thereof and to the beam *a* near the rear end thereof, a 60 similar brace *c'* being secured to the forward end portion of the beam *b'* and also to the rear end portion of the beam *a'*, and a platform *d* composed of either wood or metal is placed upon the beams and secured on the 65 top thereof by bolts *e* and *e'*, the beams being parallel one to another, and the platform extending across the middle portions of the beams. The beam *b* has a draft rod *f* connected to the forward end thereof and a similar rod *f'* is connected to the forward end of the beam *b'*, a chain *g* being connected to the rods and has a link *g'* thereon that may be shifted so as to engage either link of the chain for draft purposes. The blades *h* and *h'* are 75 formed preferably of relatively thin sheet steel, and have plates *i* and *i'* secured suitably to the rear sides thereof, the plates having angle flanges *j* and *j'* respectively that are flush with the tops of the blades. An 80 arm *k* has a foot *k'* by which it is secured on the top of the flange *j*, the arm being preferably composed of two thicknesses of iron, so as to be amply strong, and it is connected by a pivot *l* to the forward ends of the beams 85 *a* and *a'*.

A lever *m* has feet *m'* by which it is secured rigidly on the top of the flange *j'*. A coupling rod *n* is connected by a pivot *n'* to the end of the arm *k* and by a pivot *n''* to the 90 body part of the lever *m*, the latter being provided with a guide finger *m''* arranged somewhat above the pivot *n''*. A curved latch bar *o* is suitably attached to the beams *a* and *a'* and extends between the lever *m* and the 95 finger *m''*, the bar having holes *o'* therein. The lever *m* has ears *p* formed thereon to which a latch lever *q* is pivoted, the lower end of the lever having a latch bolt *r* secured thereto that normally enters either of the holes *o'* and extends through a hole *o''* that preferably is formed in the lever *m*, the latch bolt being guided in the finger *m''* and spring-pressed to its normal position by a spring *s* seated between the finger and the end of the 105 latch lever. A pair of arms *t* and *t'* are rigidly secured on the tops of the flanges *j* and *j'* respectively, and the tops of the arms are connected by a coupling rod *u*, the arms being connected to the beam *b* by pivots *v* 110 and *v'*. Two similar arms *w* and *w'* are rigidly attached to the opposite end portions of

the flanges j and j' and are connected to the beam b by pivots x and x' , the ends of the arms being connected together by a coupling rod u by means of pivots y and y' , the rod u having pivots z and z' so that all of the arms that are attached to the flanges of the blades will operate simultaneously, the pivots of the arms that are attached to the flange of the blade h being in alinement, and the pivots of the other arms being in alinement.

It will be understood that the above description refers to the drag in its most simple form of construction, and that additional blades may be employed if desired and arranged similarly to those above described.

In practical use, if it is desired to move the drag squarely, the link g' should be connected to the middle link of the chain g , but if one end of the drag is to be drawn ahead of the opposite end, then the link g' should be shifted to a suitable position at either side of the middle of the chain, and the link will remain at the desired position, being designed to engage either link flatwise between the ends of two other links. The lever m should be moved and adjusted so as to adjust the blades to suit requirements, the driver standing on the platform d . The results of operation will readily be understood from the foregoing description.

Having thus described the invention, what is claimed as new is—

1. A road drag including a frame comprising two end beams, two main beams between the end beams, an angle brace attached to the forward end portion of one of the end beams and to the rear end portion of one of the main beams, an angle brace attached to the forward end portion of the other one of the end beams and to the rear end portion of the other one of the main beams, and a platform extending across the tops of the main beams and secured to the end beams, with a plurality of blades connected to the beams.

2. A road drag including a frame comprising two end beams and two main beams between the end beams, each end beam having a plurality of arms pivoted thereto, a plurality of blades each attached to a plurality of the arms, an arm pivoted to the two main beams and attached to one of the blades, a lever pivoted to the two main beams and attached to another one of the blades, a coupling rod pivoted at one end thereof to the lever and pivoted also to the arm that is pivoted to the main beams, a curved latch bar attached to the two main beams, and a latch mounted on the lever to engage the latch bar.

3. A road drag including two end beams having each an angle brace attached thereto

and having also a plurality of arms pivoted thereto, two main beams having an arm and also a lever pivoted thereto, one of the main beams being attached to one of the angle braces and the other one of the beams attached to the other one of the braces, said lever and said arms extending up beyond the beams, a plurality of blades one of which is attached to a plurality of the arms and another one of which is attached to the lever and also to a plurality of the arms, a coupling rod pivoted to the lever and also to the arm that is pivoted to the two main beams, said rod being arranged in a plane above the main beams, a coupling rod connected to an arm of one of the blades and also to an arm of another one of the blades above the plane of the beams, a coupling rod connected to another arm of one of the blades and also to another arm of another one of the blades above the plane of the beams, and a draft chain connected with the two end beams.

4. In a road drag, the combination of a frame comprising a plurality of main beams, a plurality of end beams that are longer than the main beams, an angle brace attached to the forward end of one of the end beams and to the rear end of one of the main beams, an angle brace attached to the forward end of the other end beam and to the rear end of the other main beam, and a platform extending across the middle portions of the plurality of beams and secured thereto, with draft links connected to the forward ends of the end beams near the angle braces, and blades connected with the beams.

5. In a road drag, the combination of a plurality of end beams having each a draft rod connected thereto, a chain connected to the draft rods, a plurality of blades having each a flange at the top thereof and each flange having a plurality of arms secured thereto, one of the flanges having a lever secured thereto that has a latch thereon, a plurality of main beams, a pivot connecting the lever to the main beams, pivots connecting one of the arms to the main beams, pivots connecting the remaining arms to the end beams, coupling rods connecting one of the arms with the lever, coupling rods connecting the remaining arms of one blade with the arms of another blade, and a latch bar secured to the main beams to be engaged by the latch.

In testimony whereof, I affix my signature in presence of two witnesses.

FRANK E. OTT.
